UNITED STATES PATENT OFFICE.

EDWARD FRANCIS O'HAVER, OF CARLISLE, INDIANA.

ROTARY ENGINE.

1,176,481.

Specification of Letters Patent. Patented Mar. 21, 1916.

Application filed June 9, 1915. Serial No. 33,072.

To all whom it may concern:

Be it known that I, EDWARD F. O'HAVER, a citizen of the United States, and a resident of Carlisle, in the county of Sullivan and State of Indiana, have invented a new and Improved Rotary Engine, of which the following is a full, clear, and exact description.

My invention relates to rotary engines suitable for operation by aid of explosive mixtures or by pressure of a steadily flowing elastic medium, such as compressed air.

More particularly stated, I seek to produce a rotary engine having comparatively few parts and so arranged that the movement 15 of the rotary piston causes the latter to directly engage, and operate step by step, a single revoluble member which performs many of the functions usually performed by more complicated mechanism for applying power 20 to the piston.

Reference is made to the accompanying drawings forming a part of this specification, in which like letters indicate like parts in all the views.

Figure 1 is a side view partly in elevation and partly in section showing my improved rotary engine; Fig. 2 is a section substantially on the line 2—2 of Fig. 1, looking in the direction of the arrow; Fig. 3 is a detail 30 showing in fragmentary elevation the means provided for stopping certain revoluble parts in exact predetermined positions.

The casing is shown at 3 and has generally the approximate form of a disk. Ex- 35 tending axially through the casing and revoluble relatively to the same is a shaft 5. Carried by this shaft and located adjacent one end thereof is a cam ring 6 carrying a cam 7. Engaging this cam ring is a roller 40 8 which is carried by a fork 9, the latter being mounted upon one end of a thrust rod 10. This thrust rod is mounted in bearings 11 and 12 adapted to slide relatively thereto in the general direction of its length. 45 Mounted rigidly upon the thrust rod 10 is a collar 13. Engaging this collar is a combi- 50 nation spring 14 which also engages the adjacent bearing 12. The tendency of this spring is to force the thrust rod 10 against the cam ring 6 and cam 7.

A lever 16 is connected with the thrust rod 10 by a pivot pin 15 and is also connected with a stationary arm 17 by a pivot pin 17^a. A valve stem 18 is connected with 55 the lever 16 by a pin 19. This valve stem

carries a valve 20 and this valve normally closes an opening 21, this opening being essentially a passage in a pocket 22 of the casing, as indicated in Fig. 2. The valve 20 is contained within a valve chamber 23. A 60 spiral spring 24 is housed within this valve chamber and engages the valve 20 and also a closure plug 25 through which the valve stem 18 extends. A spark plug 26 is fitted into the wall of the pocket 22 and is used 65 for igniting the explosive mixture in instances where the same is employed. An inlet pipe is shown at 28 and is connected by aid of a fitting 27 with the adjacent portion of the casing.

A housing 29 having a general arcuate form is carried by the casing 3. Revolubly mounted within this housing is a hub 30 carrying a number of vanes 31, in this instance four, the vanes being integral with 70 the hub which is mounted upon a shaft 32. The housing 29 is provided with a sleeve 33 extending radially outward and mounted within this sleeve is a pawl 34 which extends a slight distance inward toward the shaft 80 32, as may be understood from Fig. 1. The pawl 34 carries a pin 35 which is rigid relatively to it. A spiral spring 36 encircles the pin 35 and engages the pawl 34. A needle 37 carried by a screw plug 38 has a sub- 85 stantially cylindrical form and fits loosely over the pin 35. The pawl 34 is normally pressed to its limit at the left according to Fig. 1 by the spring 36, but by compression of this spring the pawl may be moved 90 slightly to the right. When any one of the vanes 31 is moved in a clockwise direction so as to engage the pawl 34 the pawl is forced to the right, this compressing the spring 36. For this purpose the pawl 34 is 95 slightly beveled, as will be understood from this figure. The exhaust pipe is shown at 39 and communicates with the casing 3 by aid of a passage 40.

The piston is shown at 41 and is revoluble 100 in this instance in a contra-clockwise direction, as indicated in Fig. 1. The piston has a general annular form and is supported upon spokes 42 and a hub 43. The piston carries an abutment 44 extending out- 105 wardly from it at an angle, the general plane of this abutment being tangential to an imaginary circle of smaller diameter than that of the casing 3. The abutment 44 at its outer edge is provided with a portion 110

45 of arcuate form, this portion being adapted to fit airtight against the adjacent inner surface of the casing.

The shaft 32 extends entirely through the 5 housing 29 and at one of its ends carries a stop wheel 46. This stop wheel is provided with a number of notches, these notches having rounded walls. A spring pawl 48 supported by the housing is so positioned as to 10 slip or click into the notches 47 as the stop wheel 46 is rotated step by step.

The operation of my device is as follows: The parts being assembled and arranged as 15 described, a supply of elastic medium is directed through the passage 20 and into the casing at a point between the abutment 44 and between two of the vanes 30, as indicated in Fig. 1. If the medium thus introduced be an explosive mixture it is ignited 20 by aid of the spark plug 26. If it be a non-explosive medium, such as compressed air, the spark plug is not used. The valve 20 is tripped periodically by movements of the cam 7, thrust rod 10 and lever 16, so as to 25 admit the motive fluid. Each time the abutment 44 comes around it engages the adjacent vane 31 and thrusts the hub 30 carrying all of the vanes to a distance representing one quarter of the revolution. The 30 momentum given these revoluble parts tends to carry them around a little farther than they would be moved by piston motion but the stop wheel 46 does not move but one quarter of a revolution owing to the 35 action of the pawl 48 which clicks into the next successive notch from the one from which it has just been released. Thus the vanes 30 move step by step one quarter of a revolution at each step and then become 40 fixed. The pressure of the motive fluid against the abutment 44 causes the piston to turn, and in each instance, when the abutment 44 passes the passage 40, a discharge takes place through the exhaust pipe 39.

45 What I claim is:

1. In a rotary engine, the combination of 50 a casing, a revoluble piston, an abutment carried thereby, and extending outwardly at an angle therefrom, a revoluble member to be engaged by said piston and moved step by step by direct pressure thereof, a pawl for preventing retrogression of said revol-

uble member, a stop device for said revoluble member and means for supplying an elastic medium into said casing at a point 55 between said revoluble member and said abutment.

2. A rotary engine, comprising a casing, a revoluble piston mounted therein, an abutment carried by said piston and extending 60 in a plane tangential to a circle of smaller diameter than said piston, a revoluble member provided with vanes each adapted to extend partially into the path of travel of said abutment so that said abutment 65 engages said vanes in succession and moves them step by step by its direct pressure against them, a pawl normally extending partially into the path of rotation of said vanes for engaging each vane in succession 70 and preventing backward rotation of said revoluble member, and mechanism for directing an elastic fluid medium into said casing at a point between one of said vanes and said abutment. 75

3. A rotary engine, comprising a casing, a revoluble piston mounted therein, an abutment carried by said piston, and extending at an angle therefrom, a housing mounted upon said casing and having a general arcuate form, a revoluble member mounted within said housing and provided with a plurality of vanes, a pawl carried by said housing and normally extending into the path of travel of each of said vanes for the 80 purpose of being engaged by said vanes and thus preventing backward rotation of said revoluble member; a stop wheel carried by the shaft of the revoluble member and provided with notches, a spring 85 pawl adapted to successively engage said notches as the stop wheel is rotated, a valve for admitting an elastic medium into said casing at a point between one of said vanes and said abutment, and cam mechanism 90 connected with said valve for actuating the same periodically.

In testimony whereof I have signed my name to this specification in the presence of two subserioing witnesses.

EDWARD FRANCIS O'HAVER.
